(57) **CLAIM**

The ornamental design for a power bank as shown and described.

DESCRIPTION

FIG. 1 is a front and bottom perspective view showing of a power bank showing my new design;

FIG. 2 is a rear and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view of a portion indicated with numeric 9 in FIG. 1;

FIG. 10 is an enlarged partial view of a portion indicated with numeric 10 in FIG. 1;

FIG. 11 is an enlarged partial view of a portion indicated with numeric 11 in FIG. 1; and,

FIG. 12 is an enlarged partial view of a portion indicated with numeric 12 in FIG. 2.

The broken lines in the figures illustrate portions of the power bank that form no part of the claimed design.

1 Claim, 12 Drawing Sheets
